Act 25, A.D.
Apr 24, 1875 - D. M. C.

UNITED STATES PATENT OFFICE.

HERMAN IHLENBURG, OF PHILADELPHIA, PENNSYLVANIA, ASSIGNOR TO MACKELLAR, SMITHS & JORDAN, OF SAME PLACE.

DESIGN FOR A FONT OF PRINTING-TYPES.

Specification forming part of Design No. 8,308, dated May 4, 1875; application filed March 10, 1875.
[Term of Patent 7 years.]

To all whom it may concern:

Be it known that I, HERMAN IHLENBURG, (assignor to MacKellar, Smiths & Jordan,) of the city and county of Philadelphia, Pennsylvania, have invented and originated a new and original Design for a Font of Printing-Types, of which the following is a specification:

The nature of my design is fully illustrated in the accompanying typographic impression, to which reference is made; and consists of a black letter, ornamented and shaded, as shown.

What I claim as new is—

The design for a font of printing-types, as shown.

HERMAN IHLENBURG.

In presence of—

C. F. HUCH,
GEO. WM. WITHAM.
